UNITED STATES PATENT OFFICE.

PETER LOCKIE, OF ROCHESTER, NEW YORK.

IMPROVEMENT IN ARTIFICIAL LEGS.

Specification forming part of Letters Patent No. 40,417, dated October 27, 1863.

To all whom it may concern:

Be it known that I, PETER LOCKIE, of Rochester, in the county of Monroe and State of New York, have invented certain new and useful Improvements in Artificial Legs; and I do hereby declare that the following is a full, clear, and exact description thereof, reference being had to the accompanying drawings, making a part of this specification, in which—

Figure 1 is a vertical central section of the invention. Fig. 2 is a transverse section taken in the direction of the red line in Fig. 1. Fig. 3 is a plan of the joint-block or saddle C.

Similar letters indicate corresponding parts in the several drawings.

This invention consists in providing the feet of artificial legs with a fixed adjusting lever or standard running up centrally in the shell of the leg, to a proper height, and connecting it at the top with a suitable spring or springs, the tension of which may be adjusted by a set-screw, and which is so set as to just support the foot. The action of the latter is thus rendered easier and more natural than is that of those now in use, especially when the foot is placed forward in walking. The draft of the spring being in a line with the lever or standard, the position of the foot must be changed considerably before the spring is required to stretch much, and by this means is avoided the second sound or "clap," caused when the ball of the foot strikes the ground, so common with other artificial legs.

To enable others skilled in the art to make and use my invention, I will proceed to describe its construction and operation.

The shell A and foot B may be made of any suitable material or form. The top of the foot, at the ankle, is recessed out, as seen in Figs. 1 and 2, to receive the joint-block or saddle C, which may be made of wood, horn, or other equivalent. There is a recess, n', formed in front and rear, as seen in Fig. 1, in which the ends of the pivot v are fixed, it being held in position by passing through the eye of the adjusting-lever f, which latter is put through the foot and firmly held by the nut o. The pivot i passes through the block C at right angles with v, as seen in Figs. 2 and 3, and has its bearings formed in the bot-

tom of the blocks k, as seen in Fig. 2, they being fixed to the base of the leg for that purpose; or, if desired, the pivot i may be fixed in the blocks k. In either case the working-bearings should be cushioned with rawhide or similar substance. The adjusting-lever f passes loosely through the mortise s' in the block C. The spiral spring S may be covered with soft leather, and its hooks cushioned with rawhide to prevent their wearing. This spring is hooked to the lever f and the hanger d. The latter passes up through the bridge D, and is secured by the set-nut b. There may be a washer, a, of leather put between the nut and the bridge to prevent any chafing between them; or there may be a spiral or other spring substituted at this point for the spring S, or the lever f may be made to act as a spring itself, in which case the block C and pivots v and i should be connected together and hinged to the foot and leg, and the top of the lever f passed loosely through the bridge D. There is a stop-hook, g, secured through the heel of the foot B by the set-nut n. The pin c, on which the hook catches, has a cushion, e, of rubber. There is a similar stop-hook, h, attached to the bridge D, when a knee-joint is required, in which case the joint-ears E must also be applied to the shell A. The joint-block C is placed upon the fixed pivot v. The leg A is then placed in position upon the pivot i. This produces a simple, cheap, and very durable "universal joint." The spring S is then hooked in and the nut b turned down until the spring is strained sufficiently to hold the foot and boot or shoe in position. The foot may be hung with the toes elevated or depressed from their present position by bending the top of the adjusting-lever f forward or back of its present relative direction from the foot, as seen in Fig. 1. It will be seen that when the foot is forced out of its set position, in any direction, the top of the lever f is carried in the opposite direction, out of a straight line with the ankle-joint and the hook d, and the spring S is strained in proportion to the greater or less movement of the foot, and therefore as soon as it is released from such pressure the spring causes the adjusting-lever f to resume its natural direction, and with it the foot. When the

latter is elevated, as shown by the dotted lines at B', Fig. 1, the stop-hook *g* catches the pin *c* and prevents a further change in that direction. The limit of this movement may be increased or diminished, by means of the set-nut *n*, whereby the hook *g* is lengthened or shortened. This position of the foot carries the top of the adjusting-lever *f* back, as shown by the dotted lines *f'*, which, of course, stretches the spring *S*. The toe may be depressed until the edge of the shell strikes at *t* within the guard *u*.

What I claim as my invention, and desire to secure by Letters Patent, is—

The employment or use of the adjusting lever or standard *f*, (fixed to the foot,) in combination with a suitable spring or springs, for the purpose of regulating the position of the foot *B*, substantially in the manner specified.

PETER LOCKIE.
